UNITED STATES PATENT OFFICE

JOHN M. CLARK, OF NEW YORK, N. Y.

EMERGENCY FEEDER DEVICE FOR SUBMARINES

Application filed February 25, 1928, Serial No. 256,969. Renewed August 23, 1930.

The device, the subject of this invention, is a means for injecting or introducing emergency supplies or air, or food, or any other requirement into a submarine when the submarine is submerged, and particularly at a time when through accident or otherwise, the submarine is out of control, or has founded.

An object of the invention is to provide means for introducing supplies or air into any one of the compartments of the submarine, or into any one of a number of the compartments.

Another object of the invention is to provide a device of this nature, so constructed and arranged that it will not interfere with the ordinary operation of the submarine, nor to a great extent, with the free deck space thereof.

Another object of the invention is to provide a device that will be safe, and to that end, I provide means whereby the device cannot be wholly closed until parts thereof are closed, and another object of the invention is to provide a device that will be simple and easy to operate, and yet entirely efficient, and one that will not admit to the submarine, a great amount of water when the connection is being made from the outside, even when the submarine is submerged.

With these objects in view, the following is what I consider the best means of carrying out my invention, and the accompanying drawing should be referred to for a complete understanding of the specification which follows.

In the drawing:—

Fig. 1, shows a side elevation of a submarine.

Fig. 2, shows a greatly enlarged view in elevation, partly in section of my device.

Fig. 3, is a further enlarged view of a part of the device, and

Fig. 4, is a top plan view of the device shown in Fig. 3.

Similar reference numerals indicate like parts in all the figures where they appear.

In Fig. 1, I show in the merest outline, a submarine of a common type, and as no material change is to be made in the construction

of the submarine, or in the location of any of its necessary parts, or devices, I will refer to the submarine as a whole, with the reference character 1, indicating the deck thereof, at 2, and the sponsons or buoyancy tanks, with 55 a reference character 3.

Arranged upon the deck, and at any convenient point, are a plurality of housings, or caps. In Fig. 1, these caps, of which five are shown, are extremely exaggerated. Their 60 proportion, would of course, not be as great as indicated, but the size of these housings may be varied at will, and to meet the requirements.

In Fig. 1, I have shown five such housings, 65 indicating with the reference characters 4, 5, 6, 7, and 8, and it should be understood that any number of such housings may be supplied, and that they may be arranged in the most suitable and convenient place. In Fig. 70 2, I show one of the housings, together with the mechanism which it encloses, selecting the housing 5 for this exposition.

It will be noted that this housing 5 is provided with a hinge 6, and a wing nut or other suitable securing means, as shown at 5'. It will be noted that the housing is also provided with a plurality of perforations, as shown at 9, 10 and 11. These perforations indicate that the housing need not be waterproof, and I prefer that it should not be waterproof, as to make it so, would make it difficult to operate from the exterior when the submarine is submerged. The perforations 8 to 11, are therefore for the purpose 80 of closing the pressure on both sides of the housing.

Arranged within the housing, is a gate valve, as shown at 12, with a suitable operating wheel 13. I have previously stated that an object of the invention is to provide means whereby the device cannot be closed until all of its parts are closed. If the gate valve 12 is open, the wheel will project to a point suggested by the dotted line 14, or to a point somewhere between its present full line position, and the dotted line position. While in any one of these positions, the housing 5 cannot be closed, it cannot actually be closed 90 until the valve 12 is closed.

Secured to the valve 12, and projecting upward therefrom, is a screw threaded nipple 15, by means of which an air pipe or other tube may be connected to the valve 12.

Connected to the valve 12, is a pipe 16 which extends into the submarine, and into a compartment thereof. The inner end of this pipe is also provided with a valve, as shown at 17, which may be in all respects, similar 10 to the valve 12. I prefer that both of these valves should be gate valves, although any type of straight full opening valve may be employed.

Arranged under the valve 17, I may provide 15 a basket 18 for a purpose that shall appear later.

I appreciate that if a submarine is submerged to any great depth, considerable pressure will be exerted upon the disk of the valve 20 12, and it may be found difficult to open this valve. I therefore provide a short pipe 19, and a pet-cock 20, by means of which water may be admitted to the pipe 16, and the pressure in the pipe, equalized with the 25 pressure exterior to the valve 12.

In the operation of my device, I provide a plurality of cylinders, such as that shown at 30 21, in Fig. 3. These cylinders should be of metal, and are provided with a closure cap 22. The seat 23 between the cap and cylinder, should be a ground seat, as gaskets are apt 35 to become jammed or cemented tight by oxidation, and it is my intention that the cylinders 21 should be opened easily.

To introduce supplies into the submarine, loaded cylinders are provided, and a diver opening the housing 5, may open the pet-cock 20 to equalize the pressure on both 40 sides of the valve 12, and may then open the valve 12 water wheel, of course entering the tube 16, but the introduction of the cylinder 21, will displace much of the water from the tube 16. Thereupon the valve 12 and the pet-cock 20 are closed, and a signal given 45 to the interior of the submarine, and thereupon those within the submarine, may open the pet-cock 24 to equalize the pressure on both sides of the valve 17. The cylinders 21 in the pipe 16, will thereupon drop into the 50 basket 18, to be removed therefrom, as and when required.

It is my desire that this device should not be so large as to prove annoying, or as to take up space which might be otherwise utilized, and as I fully appreciate the crowded 55 condition of the interior of the submarine, I have planned that the pipe 16 may be as small as two inches in diameter, and with this size, the valves and the housing and all 60 parts of my device will be so small as to be almost inconspicuous, but will be ready in use when emergency requires.

It will of course be understood that pipes such as 16, with its accompanying valves, 65 may be introduced at any point, and if not

convenient to arrange the housings on deck, they may be arranged on the sponsons or ballast tanks. The only change that would be required, would be to increase the length of the pipe 16. This might be an advantage, 70 as it would make it possible to employ longer cylinders. While the housings, such as 5, may be omitted, I prefer that they be employed for the reason that they will prevent the valves, such as 12, being torn away, and 75 will also "flush up" deck space, or sides, and will also prevent the possibility of a valve 12 being opened accidentally or inadvertently when the submarine is in ordinary operation, or being left open after the device has been 80 submitted to its usual test or inspection.

I also prefer that the cylinders 21 shall be of the maximum possible length so that the amount of water introduced into the submarine with each operation of my device, will 85 be minimized to the greatest possible degree.

Having carefully and fully described my invention, what I claim and desire to secure by Letters Patent is:—

1. An emergency feeder device for submarines comprising an enlarged tubular member extending through the skin of a submarine, a plurality of valves, one at each end of said tubular member and means for equalizing the pressure at each side of each said 90 valve prior to the opening thereof.

2. An emergency feeder device for submarines comprising a pipe extending through the wall of said submarine, a valve interior and exterior of said submarine, and a housing for the exterior valve, the stem of said valve extending into the path of said housing and adapted to prevent the closing of the housing while said valve is open.

3. An emergency feeder device for submarines comprising a pipe entering through the wall of said submarine, a valve at each end of said pipe and adapted to a full opening, and a container adapted to be introduced into said pipe through one of said valves, said container being of a length approximately equal to the distance between the closure disks of both said valves.

JOHN M. CLARK.
